UNITED STATES PATENT OFFICE

2,023,052

WINDOW CONSTRUCTION

Clarence E. Julin, Jamestown, N. Y.

Application March 1, 1932, Serial No. 596,097

1 Claim. (Cl. 189—72)

This invention relates to new and useful improvements in window constructions and more particularly to an improvement on my Patent #1,886,105, issued November 1, 1932.

5 The principal objects of this invention are to provide a window construction embodying screen sections, ordinary sash sections, storm window sections, with weather strip and weather proof features, and with novel latch means whereby 10 these sections can be readily positioned and secured against displacement.

Another important object of the present invention over my Patent #1,886,105, is the provision of means to establish a substantially 15 weather-proof window by interlocking the section in a novel fashion.

20 Still another important object of the invention is to provide a window construction wherein the panes are mounted in a novel manner permitting mountability and demountability with ease.

These and other important objects and advantages of the invention will become apparent to the reader of the following specification.

25 In the drawings:—

Figure 1 represents a diagrammatic view disclosing the screen sections in useful position.

Fig. 2 represents a diagrammatic view showing the storm window sections in useful position.

30 Fig. 3 represents a diagrammatic view disclosing the ordinary window sections in useful position.

Fig. 4 represents a fragmentary vertical sectional view through the window construction showing all of the window sections in useful position.

35 Fig. 5 represents a fragmentary vertical sectional view showing the latch means for the window section.

Fig. 6 represents a fragmentary horizontal sectional view disclosing the various sections and their counter-balancing means.

40 Fig. 7 represents a fragmentary front elevational view of one of the pane retaining frames.

45 Fig. 8 represents a fragmentary vertical sectional view taken substantially on the line 8—8 of Fig. 1.

Fig. 9 represents a sectional view through the roller mount also shown in Fig. 5 in section.

50 Fig. 10 represents an elevational view of one of the rollers and its supporting block.

Fig. 11 represents a perspective view of one of the slide bars.

55 Referring to the drawings wherein like numerals designate like parts, it can be seen in Fig. 1, that numeral 5 generally refers to the screen sections each of which is provided with latch mechanisms 6 which form an important part of the present invention.

60 Another important feature of the invention is

embodied in the novel interconnecting means generally referred to by numerals 7 and 8. The sections of the screen assembly 5 are provided with the roller mounts generally referred to by numeral 9 and with the counter-balancing means 10 which is located in the compartments 11 and 12 at the side of the window construction. 5

Fig. 2 also shows a view similar to Fig. 1, but showing the storm window section generally referred to by numeral 13. Each of these sections 10 13 is provided with a novel latch means heretofore referred to by numeral 6, and these storm window sections 13 are also interlocked together in the novel manner denoted generally by numeral 14 (see Fig. 4). The storm window sections 13 are also provided with the roller mounts 15 and the counter-balancing means 16 in the aforementioned side compartments 11 and 12. 15

Fig. 2 also shows the lower compartment 17 for the aforementioned screen section 5 and the upper compartment 18 which serves to receive the storm window section 13. Generally speaking, the screen window sections, as well as the storm window sections, and their counter-balancing means form part of my Patent 20 #1,886,105 and in this connection, other features 25 of construction in these views not specifically described in this application form part of my aforesaid patent.

Fig. 3 discloses the conventional window sashes 30 19 which are slidable in relation to each other the same as the conventional sliding sashes now in general use. These sashes 19 are equipped with the counter-balancing means 20 which form 35 part of my Patent #1,886,105 and the sashes of these window sections 19 are also provided with the same novel fastening means heretofore referred to by numeral 6.

It can be seen that the sections of the windows 40 5 and 13 are each provided with a hollow metallic frame 21 formed at its inner side to provide an abutment 22, the abutment 22 of the screen sections 5 being offset laterally as at 23 to engage over the lateral rib 24 which is located on the screen edge portion. Each of these frames 21 is provided at its inner perimeter with the trough 45 25 which is set obliquely with respect to the corresponding pane 26 of the window construction 13 or in relation to the screen shaft 27 of the 50 screen assembly 5.

To retain the panes and screen sheet 27 in place, a retaining frame such as is generally referred to by numeral 28 in Fig. 7 is employed, and is made up of four sections. Each of the 55 sections has a reduced extension 29 having a pocket 30 for receiving the beveled extension 31 of an adjoining section and similar to its own opposite end.

The sections of the retaining frame 28 are 60 provided with tool engaging openings 32. Ob-

viously, these sections are forced into the troughs 25 and by force are fed inwardly until the ends of the frame sections abut in the interlocking portion shown in Fig. 7. Thus the sections of the frame will afford a tension against the panes 26 or seat sections 27 to prevent displacement thereof.

Each of the frames 21 is provided with an additional trough 33 for receiving a weather-stripping 34 that is attached to slide 35 and said slides 35 are also provided with roller mounts 15 for screen and storm sections, and furthermore, these frames 21 are provided with roller mounts 35 slidable in the guide 36 and from which the same are to be detached when the sections are to be removed from the window openings.

The conventional window sashes 19 are also equipped with the frame 21 and with the retaining frames 28, these window sashes being also equipped with the aforementioned weather-stripping 34, but are slidable independently of the guide 36, which is in this case primarily for the counter-balancing means 20, although the same forms no part of the present invention.

As is clearly shown in Fig. 4, the abutting edges of the frames 21 of the window assembly 13 having a zig-zag formation denoted by numeral 37, so that the sections of the assembly 13 will assume the interlocked water-proof connections clearly shown.

The sections of the screen assembly 5 are arranged in pairs, there being the upper pair a—a and the lower pair b—b, with a frame 21 for each pair. However the screen sheets 27 in themselves are provided with laterally disposed frame-like rib formations 38, each crossed so as to receive each other in the interlocking union disclosed in Fig. 8.

The frames 21 of the screen assembly 5 have their abutting portions formed in a zig-zag manner transversely thereof to form the interlocking connection denoted in Fig. 4 by numeral 37. Furthermore, the abutting portions of the frames 21 of the conventional sashes 19 are also of zig-zag formation as denoted by numeral 40 so that the same will interlock to afford a weather-proof connection.

Fig. 5 discloses a window assembly, which may be the assembly 5 or the assembly 13, but to be definite, let it be assumed that it is the assembly 13. In consistency with my Patent #1,886,105, the sections of the assembly are provided with rollers so that they will ride on the tracks 41 in the lower and upper compartments 17 and 18. The lower slide 35 is constructed somewhat differently in regard to the fastening means on the intermediate sections and a description of the lower section in regard to its fastening means will first be given.

The sectional view Fig. 5 discloses a guide 43 on which the slide bar 44 is slidable, the guide and slide bar being located horizontally within the lower portion of the frame 21 on the lower section and as is apparent in Fig. 2, a pair of these latch devices is provided for each window section.

Referring to Fig. 5 it can be seen that the frame 21 is provided with a slot 45 through which the pin 46 extends from the slide bar 44. Slidable over this opening 45 to provide a closure therefor is the plate 47 from which rises the barrel 48 forming a sleeve for the pin 46. This sleeve 48 and the head 49 of the pin 46 forms a knob facilitating actuation of the slide bar 44. The outer

end of this slide bar 44 is reduced as at 50 and provided with openings 51—52 to receive the pins 53—54 respectively.

The pin 54 swingably connects the link 55 at one end to the inner end of the reduced portion 50, while the pin 53 extends through the longitudinally extending slot 56 in the S-shaped latch member 57, which at its inner end is pivotally connected as at 58 to the guide 43, while its hooked outer end 59 engages through the opening 60 in the guide 36. The bar 44 engages in the opening of guide 36 when in secured position to carry weight of window sections.

In the guide 36 shown in Fig. 5, are the beveled bosses 61 against which the laterally disposed head 15 62 of the swingable lever 63 are engageable, the latter being swingable on the pivots 64 and urged to this securing position by the tensioning springs 65.

Obviously, when the slide bar 44 is retracted to 20 the dotted line position shown in Fig. 5, the S-shaped lever 57 moves to the dotted line position also shown in Fig. 5, thus permitting the lever 63 to engage the boss 61. In this dotted line position, the link 55 will move from the recess 66 to 25 engage the adjacent corner of the frame 21 in the recess 67. The Fig. 5 also shows that the outer end of this link 55 is swingably connected to the rod 68 which in turn at its upper end is swingably connected to the intermediate portion 30 of the hook member 69, there being a spring 70 interposed between the rod 68 and the frame 21 to maintain the hooked member 69 in the position shown in Fig. 5, engaged through the opening 71 35 in the guide 36.

However, with the bar 44 retracted to the position shown in dotted lines in Fig. 5, the hook member 69 will be retracted, so that with both the levers 57 and the members 69 disengaged from the guide 36, the frames 21 are free to be taken out, 40 provided, the corresponding latch has been retracted.

Each of the roller assemblies 15 consists of a plate 72 secured at its ends to a pair of blocks 73—73, by screws 74. These blocks 73—73 engage over the rollers 75—75, one being located on each of a pair of abutment sections 21 and 22.

As can be clearly seen in Fig. 5, the lower block 73 is grooved as at 76 to receive the outer end of the hook member 69, while the upper roller 75 is carried by a block 77 which has a groove 78 therein accommodating the head 59 of the lever 57 of the superimposed section 21. These plates 72, and their end blocks 73—73 engaging over the rollers 75—75, serve as link means for connecting the frames 21 together.

While the foregoing specification sets forth the invention in specific terms, it is to be understood that numerous changes in the shape, size and materials may be resorted to without departing from the spirit and scope of the invention as claimed hereinafter.

Having thus described my invention, what I claim as new is:—

In a closure construction comprising a window frame, a plurality of sash sections, each of the said sash sections including a hollow frame, said window frame being provided with openings therein, and latch members operative in the hollow sash frames and being engageable with the window frame at the openings thereof to retain the sections in connected relation.

CLARENCE E. JULIN.
